MASSAGE DEVICE

Julius Richard Seidel, Breslau, Germany

Application January 23, 1936, Serial No. 60,433
In Germany July 27, 1933

2 Claims. (Cl. 128—57)

This invention relates to a massage apparatus of known type consisting of a roll to be filled with hot water and having a cover of absorbent material. These massage apparatus possess the inconvenience that the cover as it is in contact with the atmosphere cools very rapidly. These apparatus are not perfect as with them massaging with steam is not possible, at the utmost they enable rubbing in of moisture by means of the absorbent cover saturated with water. Another inconvenience is that by the direct pressing on to the body of the cover saturated with water the water flows over the body of the person who is being massaged.

The massage apparatus according to the invention obviates these inconveniences. The roll to be filled with hot water has also a cover of absorbent material, but this cover is enclosed in a perforated, sieve-like envelope, preferably of rubber.

Two embodiments of the invention are illustrated by way of example in the accompanying drawing in which:—

Fig. 1 shows a massage roll in a section on line 1—1 of Fig. 2.

Fig. 2 is a cross section on line 2—2 of Fig. 1.

Fig. 3 shows in longitudinal section on line 3—3 of Fig. 4 a massage roller of modified construction.

Fig. 4 is a cross section on line 4—4 of Fig. 3.

Fig. 5 shows in elevation the massage roll illustrated in Fig. 3, the right hand handle and the cover being removed.

Fig. 6 shows on enlarged scale a portion of the envelope in flat state.

Fig. 7 is a cross section on line 7—7 of Fig. 6.

In the massage apparatus shown in Figs. 1, 2, 6, and 7 the hollow roll is designated by 1 and has on each of the end walls 2, 3 a threaded pin 4 or 5 on which a handle 6, 7 respectively has to be screwed. Holes in the end wall 2 adapted to be closed by screws 8, 9 serve the one for filling hot water into the hollow roll 1 and the other as outlet for the air. The other end wall 3 is of larger diameter than the end wall 2. The roll 1 has a cover 10 of absorbent material. A cylindrical outer cover or envelope 12, having pores 11 (Figs. 6 and 7) spaced at suitable distances and consisting preferably of rubber, encloses the cover 10. This envelope is open at one end and closed at the other end by a plate 13 having a central hole 14 through which the threaded pin 4 of end wall 2 of the roll 1 extends so that the handle 6 can be screwed on. The envelope 12 exerting the massage effect has preferably well-known

suction cups 15 (Figs. 6 and 7) designed to increase the effect of the massage. The edge of the open end of envelope 12 is lined with a metal ring 16 (Fig. 1) designed to bear on the rim of the end plate 3 of roll 1. The central hole 14 in the end plate 13 has a bush 17 of metal so that the envelope 13 can turn easily around the hollow roll 1.

The operation of the apparatus is as follows:—

The handle 6 is unscrewed and the envelope 12 removed, whereupon after removing of the screws 8 and 9 the hollow roll is filled with hot water and the screws 8 and 9 are screwed in again. The cover 10 is then soaked in hot water, the envelope 12 slipped over the cover and the handle 6 screwed on. For massaging the two handles are gripped with the hands and the rubber envelope is pressed slightly against the body and the apparatus rolled to and fro. The massage is a steam massage as the steam collecting in the space 18 between cover 10 and envelope 12 flows out through the pores 11 (Figs. 6, 7) of the envelope. As a sucking effect is further produced by the suction cups 15, the skin of the body is massaged and simultaneously treated by suction and by steam which is of great importance in respect of hygienes. Rapid cooling of the cover 10 and of the hollow roll 1 is prevented by the envelope 12.

The massage roll shown in Figs. 3 to 5 differs from that shown in Figs. 1 and 2 in that between the absorbent cover of the hollow roll and the envelope a stationary hollow cylinder is arranged which is impermeable to water and steam, but has steam outlets at the point to be placed on the body. The steam from chamber 18 is therefore conducted to the envelope and through the same on to the body only at that side of the massage apparatus which faces the body, so that no steam flows out through the pores 11 of the envelope at any other portion of this envelope. The steam is thus thoroughly utilized and the hollow roll is better protected against rapid cooling.

In this form of construction the hollow cylinder 19 has a wide slot 20 extending over almost the entire length of the cylinder and serving as steam outlet. The hollow cylinder 19 is closed at its open end by a plate 21 in which engage small pins 22 (Fig. 3) fixed on the end plate 3 of the hollow roll 1, and which has a central aperture 23 serving as passage for the threaded pin 5.

The hollow roll 1 having been filled with hot water, the hollow cylinder 19 is slipped over roll 1 from the side at which the threaded pin 5 is, until the small pins 22 engage in the holes in the

end plate 21 of the hollow cylinder, whereupon the handle 7 is screwed onto the projecting part of the threaded pin 5 and the envelope 12 is slipped from the opposite side over the hollow cylinder 19 and the handle 6 screwed on the part of the threaded pin 4 projecting from the end wall 13. The hollow roll 1 and also the cylinder 19 remain stationary during the massage as the handles 6 and 7 are gripped in the hands and the pins 22 engage in the holes of the end plate 21 of the hollow cylinder 19 so that only the envelope 12 is turned.

When the hollow rolls with electric heating device are employed, this roll need to be filled only with cold water and to be re-filled according to requirements.

I claim:—

1. A massage apparatus, comprising in combination a hollow roll for holding hot water, a cover of absorbent material on said roll, and a sieve-like perforated, removable envelope enclosing said cover. 5

2. A massage apparatus as specified in claim 1, comprising in combination with the cover and the envelope, a stationary hollow cylinder impermeable to water and steam arranged between said cover and said envelope and having an aperture serving as outlet for the steam only at that point of the massage apparatus which is in contact with the body. 10
